J. S. HUNTER

LARD REFINING DEVICE

Filed March 25, 1927

INVENTOR
J. S. HUNTER
BY *Munn & Leo*
ATTORNEYS

UNITED STATES PATENT OFFICE.

JAMES S. HUNTER, OF CHICAGO, ILLINOIS.

LARD-REFINING DEVICE.

Application filed March 25, 1927. Serial No. 178,987.

My invention relates to improvements in lard refining devices, and it consists in the combinations, constructions, and arrangements herein described and claimed.

5 An object of my invention is to provide a lard refining device with which lard may be refined more rapidly and with less manual labor.

10 A further object of my invention is to provide a device of the type described with which the operation of refining lard is more thorough and uniform.

15 A further object of my invention is to provide a device of the type described which reduces the risk of contamination to a minimum.

20 A further object of my invention is to provide a device of the type described which obviates the need of using crushed ice.

25 Other objects and advantages will appear in the following specification, and the novel features of the invention will be particularly pointed out in the appended claims.

30 My invention is illustrated in the accompanying drawings, forming part of this application, in which

Figure 1 is a side elevation of my device,

Figure 2 is an end elevation of my device, and

35 Figure 3 is a section along the line 3—3 of Figure 1.

40 In carrying out my invention, I provide a chamber or receptacle 1 having a bottom 2, a front wall 3, a rear wall 4, and tapering side walls 5 and 6. The receptacle 1 is mounted upon any suitable support indicated at 7. A lard inlet pipe 8 extends through the bottom 2 and communicates with the interior of the receptacle 1. A valve 9 is hingedly secured to the bottom 2 at 10 and adapted to swing into and out of engagement with the opening of the lard inlet pipe 8.

45 A water inlet pipe 11 passes through the rear wall 4 adjacent the bottom 2 and communicates with an annular water pipe 12 which surrounds the opening of the lard inlet 8. The annular water pipe 12 is provided with a plurality of outlet openings 13 equally spaced around the upper surface thereof.

50 An auxiliary water inlet 14 extends through the rear wall 4 substantially adjacent the upper extremity thereof and communicates with the inner portion of the receptacle 1.

55 The front wall 3 extends upwardly to a

point indicated at 15 which is a short distance from the upper extremities of the side walls 5 and 6. A chute or trough 16 is provided with a bottom portion 17 which is secured to the front wall 3, and side walls 18 which are secured to the side walls 5 and 6 of the receptacle 1. A container 19, such as a wagon or the like, is removably disposed beneath the chute 16.

60 From the foregoing description of the various parts of the device, the operation thereof may be readily understood. The receptacle 1 is first filled with cold water. This cold water may be forced into the receptacle 70 through either or both the water pipes 11 or 14. Melted lard is then forced through the lard inlet pipe 8 past the valve 9 and into the receptacle 1. As the melted lard strikes the cold water, the lard forms into a multiplicity 75 of small flakes. In this manner, the water soluble impurities are removed from the lard and received by the water. The water in its continuous flow through the water inlet pipes 11, 12 and 14 carries the flakes of lard from 80 the receptacle 1 through the chute 16 and into the container 19. The water entering the receptacle through the inlet pipe 14 forces the flakes of lard toward the chute 16.

I claim:

85 1. A lard cooling and washing device comprising a receptacle, a lard inlet pipe communicating with said receptacle, a valve disposed in said receptacle and in communication with said lard inlet pipe, an annular water inlet pipe disposed in said receptacle concentric with said lard inlet pipe and provided with a plurality of openings, and a relatively wide downwardly extending chute rigidly secured adjacent the top of said receptacle.

90 2. A lard cooling and washing device comprising a receptacle, an inlet pipe through which melted lard may be forced into said receptacle, an annular water supply pipe disposed concentric with said inlet pipe for supplying cold water to said receptacle, a valve disposed in said receptacle normally closing said inlet pipe and arranged whereby passage may be made through said inlet pipe 95 only in the direction towards the receptacle, a chute carried by said receptacle for directing water and lard therefrom and having its upper end secured adjacent the top thereof, an auxiliary water inlet pipe disposed on the 100 side of the receptacle opposite the upper end of said chute whereby the lard may be forced 105

from said receptacle into engagement with said chute, and means for receiving the lard from the chute.

3. A lard cooling and washing device comprising a receptacle having a relatively large bottom portion tapering into a relatively narrow top portion, an inlet pipe communicating with said receptacle for allowing melted lard to pass therethrough into said receptacle, means substantially surrounding said inlet pipe for forcing cold water into said receptacle for causing the melted lard into small flakes, the flakes of lard passing to the surface of the water in said receptacle, a

chute having an opened top disposed in registration with the top portion of said receptacle, a water inlet pipe disposed in communication with said receptacle at the top portion thereof for directing water under pressure toward the flakes of lard as they appear upon the surface of the water in said receptacle for forcing the flakes of lard toward and into registration with said chute, and means disposed in engagement with said lard inlet pipe for automatically closing said lard inlet pipe when said lard ceases to pass therethrough. 15 20 25

JAMES S. HUNTER.
